CLOSURE MEMBER FOR TUBE ENDS

Philip D. Becker, Hingham, Mass., assignor to
United-Carr Fastener Corporation, Cambridge,
Mass., a corporation of Massachusetts

Application June 9, 1950, Serial No. 167,130

4 Claims. (Cl. 16—42)

1

This invention relates generally to closure members and has particular reference to a plastic glide member for assembly into the end of a tubular furniture leg.

The object of the invention is to provide an improved closure member formed of a synthetic organic plastic which is adapted for assembly into the end of a tubular member.

A further object of the invention is to provide a glide which is formed of a single piece of molded synthetic organic plastic, which is adapted for assembly into the end of a tubular furniture leg to support the leg, in which the glide has means for frictional engagement with the tube wall.

A still further object of the invention is to provide a plastic glide member having an outer tube-enclosing portion and a center guide portion to initially enter the tube for positioning the glide relative to the tube to enable the end of the tube to enter the tube-enclosing portion.

Another object of the invention is to provide a glide member formed of synthetic organic plastic which is adapted for insertion into a tube for frictional engagement therewith, in which the glide member is provided with portions which are adapted to be sheared off by the tube when the glide is assembled therein.

Other objects of the invention will, in part, be obvious, and will, in part, appear hereinafter. For a fuller understanding of the nature and objects of the invention, reference should be had to the following detailed description, taken in conjunction with the accompanying drawing, in which:

Fig. 1 is a view in side elevation of a plastic glide member embodying the features of the invention;

Fig. 2 is a top plan view of the glide member of Fig. 1;

Fig. 3 is a view in elevation, partly in section, of the glide member during assembly onto a tubular member;

Fig. 4 is a view in elevation, partly in section, of the glide member taken on line 4—4 of Fig. 5 completely assembled on a tubular member; and

Fig. 5 is a view in section, taken on line 5—5 of Fig. 4.

Referring to the drawing, there is illustrated a glide member 10, which is adapted for insertion into the end of a tubular member 12, for frictional engagement with the wall 14 of the tubular member.

The tubular member 12 may be the end of the leg of an article of furniture or the like (not shown) in which case the glide 10 is adapted to bear against the floor to support the leg.

2

The glide 10 is preferably formed of a single piece of molded synthetic organic plastic, and comprises a base 16, a central tube entering guide portion 18 disposed in the base and extending upwardly therefrom, and a peripheral tube-enclosing portion 20 disposed on the base about the guide portion in spaced relation thereto to form an annular channel 22 to receive the end of the tube wall 14 when the glide is assembled.

The central guide portion 18 in the illustrated embodiment is substantially higher than the tube-enclosing portion 20, and comprises a cylindrical portion 24, having a series of longitudinal ribs 26 disposed in the outer surface thereof. The ribs 26 are preferably outwardly rounded, and increase the overall diameter of the guide portion 18 a predetermined amount, so that said overall diameter is greater than the internal diameter of the tube 12 into which the glide is to be inserted, for a purpose to be hereinafter described. The tube-enclosing portion 20 comprises an upwardly extending wall portion 28, which is integral with the base, and is tapered inwardly at the upper portion to terminate in a thin edge 30 which is adapted to fit closely about the outer periphery of the tube 12 to improve the appearance of the assembly. The wall portion 28 is preferably slightly flexible radially, and the inner surface thereof has a diameter which is substantially equal to, or only slightly less than the outside diameter of the tube 12 so as to provide frictional engagement therebetween when the glide is assembled.

The method of assembly of the glide onto the leg 12 is illustrated in Fig. 3. The guide portion 18 is inserted into the end of the tube, and since the overall diameter of the guide portion is greater than the internal diameter of the tube, the outermost portion of the ribs 26 are sheared off by the wall 14 as the glide is forced into the tube, which forms a sheared surface 32 for tight frictional engagement with the inner surface of the tube wall.

Since the center guide portion 18 extends upwardly from the base, a greater distance than the tube-enclosing portion 20, the guide portion 18 will extend a substantial distance into the tube before the tube wall 14 enters the annular channel 22. This insures that the glide is properly positioned in the tube so that the wall 14 will enter the channel 22 without damaging the thin edge 30 of the tube-enclosing portion. When the end of the tube wall is seated against the base 16, it is frictionally engaged on both the outer and inner surfaces by the glide, thereby insuring that

the glide will be securely retained in assembly with the tube.

Since plastic materials suitable for forming the glide have a coefficient of expansion substantially greater than metal, changes in the surrounding temperature will cause a considerable difference in the amount of expansion of the glide and the tube. However, since the glide engages the tube both inside and outside, an increase in temperature will cause the center guide portion to engage the inner surface of the tube more tightly, whereas a decrease in temperature will cause the tube-enclosing portion to engage the outer surface of the tube more tightly, thereby eliminating the possibility of loosening of the glide by temperature changes.

The glide may be formed of many different varieties of synthetic organic plastics, either thermosetting or thermoplastic. Materials which have been found especially adapted for this use are resins formed of ethyl cellulose, cellulose acetate, cellulose acetate butyrate, polyamide resins, vinyl resins, and methyl methacrylate.

Since certain obvious changes may be made in the device without departing from the scope of the invention, it is intended that all matter contained herein be interpreted in an illustrative and not in a limiting sense.

I claim:

1. A glide member for assembly into the end of a tubular furniture leg or the like, said member being formed of a single piece of relatively rigid molded synthetic organic plastic, and comprising a base, a tubular guide portion extending upwardly from the base, said guide portion having a series of outwardly extending tube-engaging members disposed longitudinally on the wall thereof for frictional engagement with the inner surface of the tube, a peripheral tube-enclosing portion disposed about the center guide portion, said tube-enclosing portion being adapted to engage frictionally the outer surface of the tube, said tubular guide portion being substantially higher than said tube-enclosing portion, and said tube-engaging members being spaced from the inner surface of said tube-enclosing portion a distance less than the thickness of the wall of the tubular furniture leg.

2. A closure member for insertion into the end of a tube, said member being formed of a relatively rigid synthetic organic plastic and comprising a base, a tube-entering guide portion extending upwardly from the base, said guide portion being tubular and having a series of circumferentially spaced longitudinal rib portions disposed thereon for frictional engagement with the interior sur-

face of the tube, a peripheral lip portion disposed on the base about the guide portion in spaced relation thereto, said lip portion being adapted to engage frictionally the outer surface of the tube, and said rib portion being spaced from the tube-engaging surface of the lip portion a distance less than the thickness of the wall of the tube.

3. In a closure assembly, for a support having an opening therein of a predetermined size, a closure member for insertion into the opening, said member being formed of a relatively rigid synthetic organic plastic, and comprising a base, an upwardly extending tubular member disposed on the base with circumferentially spaced longitudinal rib portions disposed thereon, said tubular member being of a smaller diameter than the support opening, and the outer surfaces of said rib portions defining a circumference of a diameter exceeding that of the support opening.

4. In a glide assembly, for a hollow tubular support leg having an internal opening of a predetermined size, a glide member formed of a relatively rigid synthetic organic plastic and comprising a base, a tubular tube-entering member extending upwardly from the base, said tube-entering portion having a circumferentially spaced series of longitudinal ribs disposed thereon, said series of ribs having an overall circumference greater than the circumference of the opening of the support leg whereby when the tube-entering portion is inserted into the tube, portions of the ribs are sheared off by the tube, and a peripheral tube-enclosing portion disposed about the tube-entering portion in spaced relation thereto to receive the wall of the tubular support leg therebetween.

PHILIP D. BECKER.
